UNITED STATES PATENT OFFICE.

JOHN LAWSON, OF CENTRAL FALLS, RHODE ISLAND.

KNITTING-MACHINE.

1,045,570.

Specification of Letters Patent. Patented Nov. 26, 1912.

Application filed January 10, 1911. Serial No. 601,894.

To all whom it may concern:

Be it known that I, JOHN LAWSON, a citizen of the United States, residing at Central Falls, in the county of Providence and State 5 of Rhode Island, have invented certain new and useful Improvements in Knitting-Machines, of which the following is a specification.

My invention relates to circular automatic stocking-knitting-machines; the invention being more especially devised to provide such machines with means, constituting a double-feed, for simultaneously knitting two independent main threads into 10 and producing the circular leg and foot portions of the stocking, one or both of said threads being inactive during the knitting of the usual heel and toe parts while the needle-cylinder is reciprocating. 15 The invention is also applicable to a circular automatic knitting-machine, which is adapted to knit what are known as split-foot stockings, either in connection with a double-feed upon the leg portion of the 20 stocking, or not, as may be desired.

In employing a second set of knitting cams, it is necessary or desirable to use in connection therewith a corresponding second sinker-cam. In knitting a stocking provided with heel and toe pockets, it is necessary that this second set of knitting-cams should be withdrawn out of action during the knitting of the heel and toe. If in such case the corresponding sinker-cam be left 30 in its normal or outward position, a sinker-wave will be formed at that point, and in the formation of the same the sinkers will be moved endwise in and out by the secondary sinker-cam, notwithstanding that no 35 knitting is being done at this point. This serves to unduly wear and abrade the thread or yarn forming the loops held upon the adjacent needles and very often to seriously injure the stocking and even render the 40 same worthless. Moreover, in machines such as illustrated in the accompanying drawings, the second set of knitting-cams and the coöperating sinker-cam are located at that part of the machine where the widening-pickers are located, and in such machine 45 the needles, on the return stroke, ride over the back of one of such widening-pickers, and so that thereby an up and down move-

ment is given to the needles at the point where the in and out movement is given 55 to the sinkers in connection with the formation of the sinker-wave. There results, therefore, at this point a double wearing action, or a see-saw action upon the loops of thread or yarn which remain upon the 60 instep-needles during the formation of the heel or toe. Moreover, the up and down movements of the needles referred to have a tendency to impart a certain amount of up and down movement to the fabric itself, 65 and if a similar wave is formed at the point where the secondary knitting-cams are located at the time such secondary cams are withdrawn so as not to operate the 70 needles, such up and down movement of the fabric will not be prevented by the sinkers because of the withdrawal of the same to form the sinker-wave.

One object of the present invention is to eliminate that portion of the wearing action 75 upon the thread or yarn above referred to which is due to the in and out movement of the sinkers at the point named, and to this end one feature of the invention consists in moving the secondary sinker-cam 80 inward at the time the secondary knitting-cams are withdrawn out of action, and so as to thus make the sinker-groove concentric at this point. By so doing, not only are the in and out movements of the sinkers 85 done away with, but the sinkers themselves, by remaining in their inner position will serve to effectually hold down the fabric at that point.

Another feature of the invention resides 90 in moving the secondary sinker-cam outward and deflecting the series of elevated instep-needles downward alternately from the ends of its needle-row to engage the secondary knitting-cams; the latter then 95 being in the outward position to clear the other or short-butt series of needles. The reason for thus retracting the secondary knitting-cams is to cause them to engage and operate only the long-butt needles. At 100 the same time the main or primary knitting-cams are inward, the corresponding sinker-cam outward, and the needle-cylinder reciprocating. These said primary and secondary knitting-cams, in connection with 105 other means, operate respectively to knit the

main and supplemental threads into semi-circular courses of stitches and interloop them together along opposite sides of the web to produce the split-foot portion of the stocking.

It may be stated here that in a knitting-machine embodying the present improvements, the needle-cylinder is normally revoluble in a contra-clockwise direction. It is, of course, also arranged to reciprocate in circular arcs, but is non-movable in a vertical direction. The main cam-ring encircling the lower portion of the cylinder is non-revoluble and is moved vertically a short distance at predetermined intervals during the production of the stocking. In fact, the movements of all the devices are automatically performed, the same being first properly positioned and timed.

In the accompanying five sheets of drawings, illustrating a circular automatic stocking-knitting machine, provided with the improvements forming the subject of the present invention, Figure 1 represents a front side elevation of said machine. Fig. 2 is a corresponding end elevation, in reduced scale, viewed from the left of Fig. 1. Fig. 3 is a transverse sectional view, in enlarged scale, taken substantially on line 3-3 of Fig. 4. Fig. 4 is a partial plan view of the upper portion of the machine, parts of the same being omitted. Fig. 4½ is a perspective view of one of the widening pickers. Fig. 5 represents a development of the main cam-ring and the two sets of knitting-cams, viewed from the inner surface of the latter. Fig. 6 is a partial plan view, in slightly reduced scale, showing the relation of the secondary knitting-cams to the needle-deflecting or wing-cams, the needle-cylinder being omitted. Fig. 7 is a perspective view, materially reduced, showing means for operating the wing-cams. Fig. 8 represents, enlarged, the outer end elevation of the intermittently actuated roller-cam. Fig. 9 is a corresponding view of its rear end. Fig. 10 represents a front side elevation of the roller-cam, &c. Fig. 11 is a transverse sectional view, slightly reduced, taken on line 50 x-x of Fig. 6. Fig. 12 is an end elevation, showing the manner of mounting one of the wing-cams, &c., viewed from the arrow direction 1, Fig. 6. Fig. 13 is a partial side elevation of the machine, viewed from the rear of Fig. 2. Fig. 14 is a partial plan and sectional view of the needle-cylinder, &c., showing the secondary sinker-cam in the normal inward position and its relation to the needles, sinkers, &c., the spacing of the needles and sinkers being greatly exaggerated to more clearly indicate said parts. Fig. 15 is a similar plan view, showing the secondary sinker-cam in the outward position; and Fig. 16 is a transverse sectional view, taken on line x-x of Fig. 14.

With the exception of the improvements forming the subject of this application for patent, the knitting-machine represented in the drawings is substantially the same as the machine illustrated in J. D. Hemphill's U. S. Patent No. 933,433, dated Sept. 7, 1909, and to which reference may be made for a more detailed description of its construction and operation.

Referring to the drawings, the swinging arm member d, arranged to guide the main knitting-thread, the radially movable sinker-cam w^x, the movable cam-block D, carrying the knitting-cams x, and the narrowing-pickers R, are located at the right of the revoluble knitting-cylinder; while diametrically opposed to said parts, being at the left of the cylinder, are located a guide d², d³ for the secondary or supplemental knitting-thread, the radially movable sinker-cam w^o, the radially movable cam-block D¹ carrying the knitting-cams x¹, and the widening-pickers T disposed above the cam-block D¹. In the following description, the said main thread, sinker-cam w^x and knitting-cams x are each designated No. 1, as No. 1 thread, &c.; and the secondary thread, sinker-cam w^o, and knitting-cams x¹ are designated No. 2, as No. 2 thread, &c.

The mechanism is mounted in and supported by a main frame or housing a and table a². The revoluble knitting or needle-cylinder N is actuated by a pair of bevel-gears n, n¹, the latter secured to the driving-shaft s carrying belt-driven pulleys p, p¹, p², suitable change-gearing and clutch b. The main cam-shaft s¹, which is actuated in an intermittent rotary manner, is located in the lower portion of said frame. To this shaft is secured a cam p⁶, which, through the medium of a spring-pressed shipper p⁵ engaging therewith and with the driving-belt, shifts the latter at predetermined intervals, so as to change the speed or stop the machine, substantially as usual. The pattern-chain B is supported by a wheel mounted on the cam-shaft and actuated intermittently by suitable means. A barrel-cam or drum f, fixed to the cam-shaft, is provided with laterally spaced, interrupted, peripheral ribs f⁶, f^{2x} and f². The main roller-cam M and also the cam A, which actuates the said secondary sinker-cam w^o, are secured to the left end of the cam-shaft. The needle-cylinder N is provided with a top ring o¹, and outer or sinker-ring n⁶, each being radially grooved to support the sinkers o; the cylinder is longitudinally grooved to receive the needles n²; one set or series of needles having short butts n³, the other series, being the instep-needles, having long butts n⁴. A top plate H, termed the cam-plate, is bored to receive the cylinder; it carries the needle-supporting ring-cam M¹, the instep-cam F, F¹, wing-cams P, P¹, and the radially mov-

able blocks D and D¹, said blocks carrying the No. 1 and No. 2 knitting-cams, respectively. The cam-plate is adapted to be moved bodily up and down a short distance at predetermined points, through the medium of the said roller-cam M and suitable intervening connections. In normal knitting, the cam-plate is in the elevated position to produce, say short loops or stitches. In order to lengthen the stitches, as for example when reinforcing threads are introduced, the cam-plate is moved downward.

A cap-ring G is located above the sinker-ring, it has an annular flange on its underside extending below the top of the member n⁶. The ring G is non-revolvble, but capable of slight angular vibratory movements in a horizontal plane. The underside of ring G is further provided with a recessed part forming an inner peripheral flange or shoulder o², having its diametrically opposite major portions concentric with the cylinder, and constituting a path for the sinkers; the arrangement being such that, when in action, the engagement of the sinkers with said concentric part of the shoulder moves them inward to the normal position to facilitate the casting off of the last-formed loops from the needles into the web. At diametrically opposite points in the plane of the recessed part, being substantially 90° with respect to the said concentric portions, the shoulder itself is recessed or cut away to form an enlargement o³ to freely permit the passage of the sinkers while they are withdrawn to pass the knitting-cams. (See Figs. 3, 14 and 15). At each of these enlarged recessed places the cap-ring is provided with a radially movable sinker-cam, before referred to, having some what the form of a crescent and disposed in a horizontal plane; its inner or concave face portion o⁴ being formed substantially concentric with the cylinder proper, and when in the inward position lying contiguous to the face of the needles. Each end of the sinker-cam is pointed and extends a short distance circumferentially past the corresponding end portion of the concentric part o², thereby, when in action and in the inward position, causing the sinkers to successively engage the outer face of the cam, the latter, in connection with the part o² of the cap-ring, then forming a continuous true circular sinker path. The outer face o¹¹ of the sinker-cam is convex, its width at the center being slightly less than the space or gap o¹⁰ (Fig. 16) lying between the two vertical arms or members of the sinker o. When the sinker-cam is moved outward (see Fig. 15) to produce the sinker-wave at the knitting-point, the sinkers then engaging the sinker-cam are thereby carried bodily and outwardly with it; the continued rotation of the cylinder causes the entire series of sinkers supported in the ring n⁶ to successively

engage the surface o¹¹ of the cam as they pass from the concentric face o², thus deflecting them outward to the apex of the cam; from this point the outer ends of the sinkers engage the cam-shaped face o³ of the ring G, thus moving them inward to engage the concentric flange part o².

A latch-ring C (Figs. 1, 2 and 3) pivoted to the fixed standard c¹ is provided at the right with an extension d¹ in which are mounted spring-pressed swinging guides d for the main and reinforcing knitting-threads. The latch-ring is also provided, at a point diametrically opposite said guides, with small eyes or openings d², d³; arranged so to receive the No. 2 or secondary main knitting-thread and guide it to the adjacent needles to be knitted into the leg and foot portions of the stocking. The latch-ring is supported in the dropped horizontal normal position by means of the stationary vertical hollow standard K.

The guides d for the No. 1 main and reinforcing knitting-threads are each controlled by a two-arm lever f⁵ pivoted in the upper portion of standard K, a swinging lever f³ (indicated in Fig. 1), a wire link f⁴ connecting the two levers, and having the front or free end of lever f³ adapted to engage with the corresponding cam-rib or flange f² of the intermittently revoluble drum f, before referred to. Similar means are employed for moving No. 1 sinker-cam w^x outward; that is to say, the sinker-cam is provided with a flat arm w¹ extending through ring G and terminating in the lateral arm w²; the inner face of the latter being engaged by the short vertical arm h² of the pivoted bell-crank lever h, the other arm being hooked into a wire link f⁴ (Figs. 3 and 4), in turn attached to the rear end of a swinging lever f^{3x}, the front end of the last-named lever being adapted to engage with a suitable peripheral cam-rib f^{2x} of the drum. The spring o⁷ moves the sinker-cam inward to its limit 110 upon the disengagement of the lever f^{3x} from the cam-rib.

The construction and function of No. 2 sinker-cam w⁰ are substantially the same as the No. 1 sinker-cam, and it is actuated as follows:—A cam A, having, as drawn, three notches or depressions a³ formed in its periphery, is secured to the roller-cam M, Fig. 8; a lever e (Figs. 2 and 13) fulcrumed at a⁵, has its front end in engagement with the periphery of cam A, its opposite end being jointed to a vertical link e¹, the latter in turn jointed to the rear end of the pivoted bent lever i. To the front end of the latter is secured the vertically guided rod i¹, its upper end portion being bent and wedge-shaped at i² and in engagement with the arm w² of the No. 2 sinker-cam. The lever i is provided with a retracting spring s² to assist in moving it downward when the 130

sinker-cam is to be moved from the outward to the inward position, the spring o^8 at the same time effecting the last-named movement. When the free end of said lever e is in engagement with the outer concentric portions of cam A, the No. 2 sinker-cam is maintained in the outward position, as in knitting the leg, split-foot and looper courses, and when the lever is engaging the respective notches a^9 the No. 2 sinker-cam is permitted to remain in the inward position, as in "running-on" the stitches and also in knitting the heel and toe parts.

The cam-block D¹ carrying the No. 2 knitting-cams x^1, x^1 , is moved inward and outward at certain points in the knitting-operation by means of a swinging lever e^8, e^4 , Figs. 4 and 6, jointed to a horizontal link b^5 , in turn jointed to an extension of the swinging lever b^4 , the latter also having an arm b^6 (Fig. 1), whose outer end is suitably connected with and adapted to move the guided instep-cams F, F¹ in a vertical direction. The lower end of said lever b^4 is connected, through the medium of a link b^8 , to the upper end of the pivoted main clutch-lever b^1 , its lower end being engageable with a suitable flange f^6 of the drum f, arranged to oscillate the lever at intervals, thereby disengaging the main clutch b from the quick-speed gearing, producing plain circular knitting, and interlocking it with mechanism arranged to move the needle-cylinder in a rotary-reciprocatory manner, as in producing the heel and toe and split-foot portions of the stocking. Upon moving the clutch in the opposite direction, the cylinder ceases its reciprocatory movements and resumes continuous rotary action. The act of thus automatically moving the clutch into engagement with the cylinder-reciprocating mechanism causes the simultaneous movement of the instep-cams F, F¹ and cam-block D¹, thereby elevating and temporarily rendering inactive the long-butt or instep-needles, the movement at the same time causing the No. 2 knitting-cams to move outward to permit the short-butt needles to move idly past them.

From the foregoing description and the accompanying drawings, it is clear that the knitting-machine is capable of employing main and secondary knitting-threads, and is provided with main and secondary knitting-cams and main and secondary sinker-cams; these knitting and sinker-cams are capable of radial in and out movements with relation to the needle-cylinder, thereby, as stated, adapting the machine to use one or both of the said threads while the cylinder is reciprocating, as well as in circular knitting.

In adapting my improved knitting-machine to produce in the foot portion of the stocking what is termed a "split-foot," a

pair of mechanically actuated wing-cams P P¹ are temporarily moved inward and brought into service. It may be again stated that the needle-cylinder is reciprocating during the production of the split-foot, the secondary knitting and sinker-cams then being in the outward or retracted positions. The reason for retracting the secondary knitting-cams at this time is to cause them to engage and operate only the long-butt needles. While the cylinder is thus reciprocating, the No. 1 knitting-cams x (the latter being in the inward position and the corresponding or No. 1 sinker-cams outward) are causing the series of short-butt needles to knit No. 1 thread into semi-courses of stitches. Concurrently with the production of the semi-courses, the conjoint action of the wing-cams P, P¹, instep-cams F, F¹, and an inclined self-dropping switch-cam z deflect the series of elevated long-butt needles downward to engage the retracted No. 2 knitting-cams x^1 and then deflect the needles back to the elevated position, thus converting No. 2 thread into semi-courses of stitches, and being complementary to the first-named semi-courses. Each semi-course of stitches of one series is at the same time interlooped or joined to each semi-course of stitches of the other series. The thus produced split-foot portion of the stocking will present a pair of longitudinally extending, diametrically opposed juncture lines where the two threads are connected.

The following describes the mechanism illustrated in Figs. 2, 6, 7, 13, &c., for simultaneously actuating and controlling the movements of the wing-cams: A small lug m is suitably positioned and secured to the main cam-roll M and projects a short distance beyond the latter's periphery to engage the front or free end m^1 of a two-arm lever a^4 pivoted on a stud a^5 . At the commencement of knitting the split-foot part, the cylinder then reciprocating, the element M in its angular movements temporarily stops (see corresponding position, Fig. 7) thereby causing the lug m to engage and move the lever a^4 , the result being to simultaneously move the two wing-cams inward so as to engage the long-butt needles. To the rear end of the lever a^4 is jointed a vertical link a^6 , connected at the upper end to a bell-crank lever a^7 , the other arm of the last named lever being jointed to a short connection a^8 , which in turn is jointed to a slidable bent band-slide E partly encircling the left end of the table a^2 and supported by screws s^4 extending therefrom through elongated holes a^9 . To the member E are secured a pair of dogs or plates r , a portion of each extending above the table and having an inclined or beveled edge part r^1 . Thus it will be seen as before stated that the rotary movements of the cam-roller causes

the lug m to engage the end m^1 of lever a^4 once per revolution, as indicated in Fig. 7, thereby, through the medium of said connections, moving the guided lever E and its cam-plates r rearwardly a short angular distance and automatically positioning the wing-cams inward to engage the long-butt needles—see Figs. 6 and 11.

The front and rear wing-cams P^1 , P , shown in Fig. 6 in the inward or operative position, as just stated, are each secured respectively to the upper arm of a swinging latch g pivoted to an ear or bracket h^5 fixed to the top of the plate H . A screw passing through a slot h^6 of the latch serves to guide the latter in its angular movements. The outer or free end of the horizontal portion g^1 of the latch is, when in use, supported by the corresponding cam-plate r and kept in normal contact with it by means of a suitably mounted spring g^2 . See also Fig. 11. When the cam-roller M , in its intermittent movements, carries the lug m past the lever a^4 , the latter, assisted by a pull-spring a^9 , Fig. 13, drops onto the concentric rim of the roller or other suitable stop, thereby, through the means described, causing the member E to advance angularly, the spring-pressed arms g^1 of the two latches mean-while sliding downward on the inclined surfaces r^1 of the members r , thus simultaneously retracting the wing-cams outward from the cylinder into the normally inactive position. In connection with the rear wing-cam P , the inclined switch-cam z , before referred to, is employed, the same being located below said wing-cam and secured to a shank z^1 mounted to oscillate in a stand or bracket h^5 ; a spring z^2 serves to keep the switch-cam in its lower inclined or normal position. See Figs. 6, 11 and 12.

In plain or regular circular knitting the butts of all the needles pass freely under the spring-pressed cam z ; but in knitting the heel and toe, the cylinder then reciprocating and the cams x^1 moved outward, both series of butts engage the upper inclined face of the cam z and are thereby deflected upward, only the long-butt needles however are then acted upon by the knitting-cams x^1 . The cylinder in its return movement, in coöperation with wing-cam P , deflects the needles downward, the long-butt needles at the same time engaging the other cam x^1 to coöperate with other members for casting off the loops of the last-named needles into the web, the other wing-cam P^1 deflecting the needles immediately thereafter into the upper inoperative plane. See Fig. 5.

In making the split-foot portion of the stocking, the normally positioned short-butt needles will, during each reciprocation of cylinder N , in connection with No. 1 knitting-cams, produce a semi-course of loops from No. 1 thread, the butts of the

needles meanwhile freely passing the inner faces of the No. 2 knitting-cams, the instep-cam and the wing-cams; the narrowing-picks then being idle. At the same time, too, the series of long-butt needles, then elevated above the working-plane of the other series of needles, are successively deflected downward by wing-cam P^1 , positioned contiguous to the instep-cam, to engage No. 2 knitting-cams to produce a semi-course of loops from No. 2 thread, the needles immediately thereafter being deflected upward between the adjacent inclined faces of the wing-cam P and switch-cam z to the elevated plane. The contrary movement of the cylinder deflects the long-butt needles downward between the said cams P and z to engage No. 2 knitting-cams, the latter, in connection with wing-cam P^1 and instep-cam, next deflect the needles upward to the elevated plane. In the development of the ring-cam M^1 , represented in Fig. 5, the irregular, fine dotted line indicates the movements of the long-butt needles when the cylinder is moving in one direction, and the coarser dotted line indicates the movements of the needles when the cylinder is rotating in a contrary direction.

I claim as my invention:—

1. A circular knitting-machine having in combination a needle-cylinder having needles and sinkers movably mounted therein, two knitting-cams, two corresponding sinker-cams, means for rendering one of said knitting-cams inactive, and means for moving both of said sinker-cams toward and from said needle-cylinder.

2. In an automatic circular stocking-knitting machine, the combination of a knitting-cylinder, needles and sinkers capable of independent movements mounted in the cylinder, main and secondary knitting-cams, means for introducing an independent knitting-thread to the needles at a point contiguous to each of the knitting-cams, a pair of sinker-cams disposed in the path of the sinkers, and means adapted to move the sinker-cams bodily toward and from the cylinder at certain points while the stocking is being produced.

3. In a circular automatic stocking-knitting machine having a knitting-cylinder provided with independently movable needles and sinkers, the combination therewith of means arranged for introducing a pair of knitting-threads to the needles, a pair of stitch-forming devices positioned with relation to both the said cylinder and thread-feeding means arranged to simultaneously convert said knitting-threads into a plurality of circular courses of stitches at each revolution of the machine, a sinker-cam located adjacent each point where the said knitting-threads are introduced to the needles and being engageable with the sinkers, and

means for moving the sinker-cams in and out with respect to the cylinder while the stocking is being produced.

4. In a knitting-machine of the general character described, the combination of a revoluble knitting-cylinder, needles and sinkers movably mounted therein and revoluble with it, a sinker-guiding path having its major portion concentric with the cylinder and provided with recesses, a sinker-cam mounted in each recess, means for moving the sinker-cams inward at predetermined times for the purpose specified, and means for moving both sinker-cams outward at predetermined points while the stocking is being knitted.

5. In a stocking-knitting machine of the general character described, the combination with a revoluble knitting-cylinder and guided latch-needles and sinkers mounted therein, of means for introducing a pair of independent main knitting-threads to the circular row of needles and converting them into two circular courses of stitches during each revolution of the cylinder, a non-revoluble sinker-cam located adjacent the point where each of said knitting-threads is introduced, and means for moving one or both sinker-cams inward during the knitting operation to prevent injurious wearing action by the sinkers upon the stitches and web supported by the inactive needles.

6. In a knitting-machine having a rotary cylinder and independently movable needles and sinkers mounted therein and revoluble with the cylinder, the combination therewith of a relatively stationary cap-ring disposed above the cylinder provided with a groove or path for guiding the sinkers inward, a pair of sinker-cams interposed in said path adapted when they are moved inward, and in coöperation with the path, to temporarily guide all the sinkers in a true circle, means

for moving the sinker-cams outward to deflect the sinkers from a circular path at 45 points contiguous to the stitch-forming places, as in normal circular knitting, and means for effecting the said inward movements of the sinker-cams.

7. In a circular automatic split-foot stocking-knitting machine, a knitting-cylinder, independently movable sinkers and long and short-butt needles mounted therein, main and secondary knitting-cams arranged with relation to the cylinder, means for operating the latter in a reciprocatory manner during the production of the split-foot portion of the stocking, and means for introducing an independent knitting-thread to the needles at each of the two stitch-forming points, the combination therewith of independently movable sinker-cams located in the path of the sinkers, means for moving said sinker-cams, means for moving the series of long-butt needles upward out of the normal knitting-plane, means for moving the secondary knitting-cams outward so as to clear the series of short-butt needles while the latter are producing from one thread a semi-course of loops, means for deflecting the long-butt needles downward into operative engagement with the secondary knitting-cams to produce from the other thread a semi-course of loops concurrently with and being joined to the first-named semi-course, and means for moving the long-butt needles back to the inoperative plane at the completion of each semi-course during the production of the split-foot.

In testimony whereof I have affixed my signature in presence of two witnesses.

JOHN LAWSON.
